CLAIM

I claim the ornamental design for a combined needle felting claw and cleaning brush for appliquéd work, as shown and described.

DESCRIPTION

FIG. 1 is a perspective view of a needle felting claw and cleaning brush for appliquéd work according to my new design;

FIG. 2 is a front view of the same;

FIG. 3 is a rear view of the same;

FIG. 4 is a top plan view of the same;

FIG. 5 is a bottom view of the same;

FIG. 6 is a left side view of the same, a right side view being a mirror image of FIG. 6; and,

FIG. 7 is a longitudinal sectional view of the same.
